UNITED STATES PATENT OFFICE.

ARTHUR PIEL, OF NEW YORK, N. Y.

MUFFLER CUT-OUT.

1,065,467.

Specification of Letters Patent. Patented June 24, 1913.

Application filed April 13, 1910. Serial No. 555,255.

To all whom it may concern:

Be it known that I, ARTHUR PIEL, a citizen of the United States, residing in the borough of Manhattan, in the city of New York and State of New York, have invented certain new and useful Improvements in Muffler Cut-Outs, of which the following is a specification.

This invention relates to improvements in muffler cut-outs, and especially to cut-outs adapted to be used with exhaust pipes of hydrocarbon engines of the compression type, although it is obvious that same can be used in connection with various other types of engines and for different purposes.

The object of the invention, primarily, is to provide means for controlling the direction of travel of the exhaust gases or vapors from an engine, and also to attain the various other effects and results hereinafter set forth.

The invention consists in providing a suitable and efficient means for controlling the exhaust vapors or gases from an engine in such a manner as to accomplish the various objects of the invention, and further consists in the new and novel features of construction and combinations of parts set forth and claimed.

In the accompanying drawings I have shown one form of mechanism embodying my improvements, in which:

Figure 1 represents a side elevation in section of a muffler cut-out showing different positions of the same. Fig. 2 represents a plan view partly in section, and Fig. 3 represents an end view of the same.

The cut-out may be placed in the exhaust pipe 1 in any suitable position between the engine (not shown) and the muffler 2, which is indicated by dotted lines in Fig. 1. The cut-out comprises a drum, chamber or resonator, having end portions 3 and a central portion 4. The end portions are cylindrical in section and preferably are slightly larger in diameter than the exhaust pipe, to which they are detachably secured by any suitable means as the flanges 5, whereby the cut-out may be removed and replaced without disturbing the alinement or position of the adjacent portions of the exhaust pipe. The central portion 4 of the drum is substantially semi-cylindrical in section, and has a diameter considerably greater than the diameter of the exhaust pipe or of the end sections which communicate with the chamber through constricted openings hav-

ing the same or approximately the same diameter as the exhaust pipe.

The cut-out pipe 6 is preferably larger in diameter than the exhaust pipe and is detachably secured to a flange 7 formed integral with the walls of the drum or resonator by any suitable means, as bolts 8, which engage with corresponding flanges 9 provided on the cut-off pipe. The connection between the drum and cut-off pipe is arranged a suitable distance below the line of the exhaust pipe. The inner portion of the flange 9 is finished to provide a valve seat 10 and also to form a sharp edge which produces a peculiar and accentuated tone effect.

The direction of travel of the gases is controlled by a valve comprising a plate 11 secured to a removable stem 12 rotatable in a bearing 14 provided partly in flange 7 of the drum, and partly in the flange 9 of the cut-off pipe. The valve is normally held in position to close the cut-off pipe, by an adjustably mounted coiled spring 15 secured at one end to the valve stem 12 and at the other end to the drum by any suitable means as the locknut 16. A lever 17 is secured to the opposite end of the valve stem, which provides means for actuating and controlling the valve. Said lever may, if desired, be counterweighted as at 18.

While the valve is in its normal position the cut off pipe is closed and the valve itself is below the line of the exhaust pipe, and the gases are free to pass directly through the chamber or resonator into the muffler without being impeded in the slightest degree. When it is desired to cause the gases to travel through the cut-out pipe the valve is raised so as to close the opening leading into the muffler, the perimeter of said opening being preferably finished to provide a seat for the valve in its raised position, so that access to the muffler will be entirely closed, and all of the gases or vapors directed through the cut-off pipe. The incoming gases strike against the valve and are deflected into the chamber, which, owing to its enlarged size, acts somewhat as a drum or resonator, thus serving to accentuate the noise of the escaping gases or vapors. As soon as the valve is released it is automatically returned to its normal position by the spring and since it is entirely below the normal line of travel of the gases, and below the level of the exhaust pipe, there is no tendency for the valve to be opened by suction.

By means of this construction the several parts of the cut-out, and particularly the valve, are readily accessible for the purpose of replacement or repair. The cut-out as a whole can be removed by loosening the holding bolts without disturbing the position or alignment of the adjacent ends of the exhaust pipe. If desired to clean the valve it is only necessary to remove the upper portion of the drum and the valve can be lifted out without loosening or detaching any other parts. The cut-off pipe can be bent in any desired direction, but preferably the gases or vapors are exhausted rearwardly in line with the muffler, so that dirt and dust will not enter and clog the valve seat or the circumference of the valve plate, which is also finished to seat tightly upon the valve seat. Since the valve seat is removable, access may be readily had to the drum without disconnecting it from the exhaust pipe line by loosening the cut-off pipe.

It is obvious that the lever 17 which actuates the valve may be set at any desired angle with respect to the valve. It is obvious also that various other changes within the skill of the mechanic may be made in the details of construction without departing from the spirit of the invention, provided the means set forth in the following claims be employed.

I claim as my invention:

1. In a muffler cut-out the combination with a chamber forming part of the exhaust pipe, of a cut-out pipe detachably secured to and communicating with said chamber and provided with a flange forming a valve seat and a valve mounted in bearings formed partly in said cut-out pipe and adapted to engage said valve seat to close said pipe.

2. In a muffler cut-out the combination with a resonator comprising cylindrical end portions secured to the exhaust pipe and a semi-cylindric central portion having a larger diameter than the end portions and communicating with said end portions through a constricted opening having the same diameter as the exhaust pipe, of a cut-off pipe secured to and communicating with the resonator, a valve controlling the opening into said cutoff pipe, said cutoff pipe being provided with a flange whereby the same is secured to the resonator, said flange being provided with a bearing for the valve and forming a seat for said valve in its closed position.

3. In a muffler cut-out the combination with a resonator comprising end portions of a diameter not less than the diameter of the exhaust pipe and a central portion of larger diameter than the exhaust pipe, a cut-out pipe communicating with said resonator, a valve in said resonator secured to a stem ro-

tatable in bearings formed partly in said resonator and partly in the wall of said pipe at the junction of said resonator and pipe, means for normally holding said valve in position to close the cut-off pipe, said valve in its closed position being arranged below the line of the exhaust pipe.

70

4. In a muffler cut-out the combination with a chamber forming part of the exhaust pipe, of a cut-out pipe communicating with said chamber and provided with a flange whereby said pipe may be detachably secured thereto, a valve in said chamber having its stem seated in bearings formed partly in the wall of said chamber and in said flange, and means for securing said cut-out to the exhaust pipe whereby it may be removed without disturbing the adjacent ends of the exhaust pipe, substantially as described.

75

5. In a muffler cut-out the combination of a cut-out pipe communicating with the exhaust pipe line and having a larger diameter than the exhaust pipe, of a valve seat on said cut-off pipe, a valve comprising a valve plate, and a removable valve stem, a spring secured to said valve stem for normally holding the valve on its seat, means for adjusting the tension of said spring, and a lever for actuating said valve, substantially as described.

80

6. A muffler cut out adapted to be attached to an exhaust pipe, comprising a chamber having an opening on one side thereof, a cut out pipe having a bore in communication with, and of less dimension than said opening, the end of said cut out pipe removably fastened to said chamber and closing said opening and provided with a valve seat, and a valve normally resting on said seat to close said cut out pipe and disposed out of line of the fluid passing through said chamber and having a pivotal connection disposed between said pipe and chamber.

90

7. As an article of manufacture, a muffler cut-out comprising a three chambered casting having a common bore, and having an inlet and an outlet at opposite ends thereof, the end chambers having a cross-sectional area greater than the corresponding area of said inlet and outlet and the middle chamber having a cross-sectional area greater than the corresponding area of said end chambers and having the openings thereto equal to the inlet and the outlet and a valve controlled outlet from said middle chamber.

110

This specification signed and witnessed this twelfth day of April, A. D., 1910.
